PHILIP KEMPTER, OF MILWAUKEE, WISCONSIN, ASSIGNOR TO GEUDER PAESCHKE & FREY COMPANY, OF MILWAUKEE, WISCONSIN, A CORPORATION OF WISCONSIN.

STRAINER.

Application filed March 26, 1926. Serial No. 97,489.

This invention relates to improvements in strainers, and more particularly to those of the type now commonly employed for straining milk as the same is poured into the large cans for shipment.

One object of the invention is to provide a strainer of the character described which shall possess certain advantages over those heretofore used, these advantages being threefold; first, the speeding up of the straining, second, the providing against accidental displacement of that part of the strainer commonly referred to as the "cap" and third, the rendering of the strainer much easier to clean.

Various other objects and advantages will appear from the following specification taken in connection with the accompanying drawings wherein one form of the invention is illustrated.

In the drawings:

Figure 1 is a side elevation of the upper portion of a milk can, showing a strainer constructed in accordance with the present invention operatively positioned therein, a portion of the can being broken away and a portion of the strainer being in section in order to better illustrate the construction;

Fig. 2 is a section on line 2—2 of Fig. 1; and

Figs. 3 and 4 are detail views illustrating the improved bayonet joint employed for fastening the cap of the strainer in position.

Referring more in detail to the drawings, the strainer as shown comprises a bowl 10 preferably of sheet metal and provided with a rolled edge 11 surrounding the upper end thereof. A cuplike element 12 provides a lower extension for the bowl in the form of a restricted neck 13, the bottom wall 14 of the cup being provided with a series of spaced apart slots 15 preferably arranged in parallel relation substantially as shown. The cup 12 is provided with a flange 16 surrounding its upper open end and this flange 16 engages and overhangs the adjacent wall of bowl 10 and is preferably spot welded or soldered thereto.

A cap 17, the bottom of which is also provided with a plurality of spaced apart slots, which latter bear reference character 18, is adapted to be fitted or telescoped upwardly over the restricted neck 13 and to clamp between the slotted walls a section of suitable

filtering material 19 which may be in the form of a piece of cloth or the like. Bayonet joints 20 of special construction serve to hold the cap in position and to prevent accidental displacement thereof. The stud of each bayonet joint bears reference character 21 and is carried by the restricted neck portion 13 of the strainer. The other member of each bayonet joint with which the stud 21 coacts in securing the cap in operative position is in the form of a tapered groove 22 provided in the adjacent side wall of the cap member 17. Each groove is merely an outward depression in the side wall of the cap, but is formed so that the depression is greatest in the vertical leg of the groove and more especially at the top end thereof, or at the point where the stud 21 first engages the groove in fitting the cap over the restricted neck portion of the strainer. From this point each groove gradually lessens in depth, this lessening continuing throughout the lateral leg of the groove until said groove at its extreme inner end merges substantially into the regular contour of the side wall of the cap substantially flush therewith. As shown the lateral legs of the bayonet grooves are slightly inclined downwardly. In assembling the cap on the lower end of the strainer, the filtering cloth or other material 19 is first placed therein over the slotted bottom wall thereof and the cap is then moved upwardly over the restricted neck 13 in such position that studs 21 may readily engage the vertical legs of grooves 22. The upward movement of the cap is then continued until the studs 21 engage the upper wall of the lateral legs of the bayonet grooves, whereupon the cap is turned in the usual manner until the ends of the studs bind firmly in the lateral legs of the grooves due to the gradual decreasing depth of said grooves as previously described. The downward inclination of the lateral legs of the bayonet grooves, it will be observed, cooperates with the studs 21 during this rotative movement of the cap and serves to draw the cap upwardly, bringing the slotted bottom thereof into firm clamping engagement with the slotted wall 14 of the restricted neck portion. In this manner, and due to the construction described, a very firm and secure connection between the cap and the restricted neck portion of the strainer is assured, and one which en-

tirely precludes the possibility of accidental displacement of the cap, such as heretofore frequently occurred. This sometimes occurred when the strainer was in position in the milk can, the cap dropping down into the can and frequently this is not discovered by the attendant until after the can has been filled.

The bayonet joints are preferably so arranged as to present the slots in the bottom of the cap 17 at substantially right angles with respect to those in the bottom wall 14 of the neck portion 13 of the strainer when the cap has been moved into final position. This relationship is shown more clearly in Figure 2 of the drawings and, as will be observed from this figure, this results in the formation of a plurality of small rectangular openings over the entire outlet end of the strainer when assembled as described. It has heretofore been proposed to provide the bottom wall of the neck portion of the strainer and the bottom of the cap portion each with a series of small circular apertures and to provide a joint between the cap and neck portion intended to ensure alignment of these apertures when the cap was moved into position, but in practice many things interfered with the alignment of the apertures and, oftentimes, these apertures would be out of line, resulting in a material slowing up of the straining operation and not infrequently in complete stoppage, the apertures in such case being directly out of line and the filtering material clamped firmly between the apertured walls so that the outlet would be entirely obstructed. As will be observed, such possibilities are entirely overcome in a construction such as herein described and illustrated, for even though the cap is not moved into precisely the same position with reference to the neck portion each time it is reapplied thereto, there will always be a free passage through the filtering material for the liquid to be strained. It is immaterial in the present strainer whether or not the respective slots are precisely at right angles with respect to each other, the desired results being obtained equally as well in any position of the cap within the range permitted by the bayonet joint. As will also be apparent, a strainer constructed as herein illustrated and described, lends itself much more readily to thorough and quick cleaning, as it is a comparatively easy matter to thoroughly clean slotted walls as compared to walls having a plurality of small apertures such as heretofore employed.

In the use of the strainer, the same is applied to a milk can substantially as shown in Fig. 1 of the drawing, the milk being poured into the upper open end of the bowl 10, filtering downwardly through the lower end of the strainer and into the can. The

upper edge of the cap 17 is preferably finished off by folding or bending the metal back upon itself, as at 23, to form a bead or the like as shown.

While the improvements have been herein illustrated and described as more especially for use in connection with milk strainers of the character mentioned, the invention, as will be readily understood, is equally adaptable to strainers of various other types and for various other uses and it is desired, therefore, that the foregoing specification and the following claims be construed accordingly.

As will be readily appreciated, the improvements are susceptible of various changes and modifications without departing from the spirit of the invention and, accordingly, it is not desired to limit or restrict the same except where limitations appear in the appended claims.

The invention claimed is:

1. A strainer comprising a bowl having a restricted neck at its lower end, a slotted wall extending across said neck, and a cap fitting over said neck, the bottom wall of said cap being also provided with slots, and a section of filtering material clamped between said slotted walls.

2. A strainer comprising a fixed wall and a removable wall, each provided with a plurality of elongated slots arranged in parallel relation, a filter pad disposed between said walls and means for ensuring the assembly of said parts in such wise that the slots in one wall will be angularly disposed with respect to the slots in the other.

3. A strainer comprising a bowl having a restricted neck at its lower end, a slotted wall extending across said neck, a cap fitting over said neck, the bottom wall of said cap being also provided with slots, a section of filtering material clamped between said slotted walls, and means for holding said cap in position.

4. A strainer comprising a receptacle, the bottom wall of which is provided with a plurality of elongated slots arranged in parallel relation, a separate member adapted to be removably clamped over said wall and similarly provided with a plurality of elongated slots arranged in parallel relation, a filter pad disposed between said wall and said member, and means for holding said member in such position that the slots therein extend at substantially right angles to those in said wall.

5. A strainer comprising a bowl having a restricted neck at its lower end, a slotted wall extending across said neck and a cap removably fitting over said neck, the bottom wall of said cap being also provided with slots, a section of filtering material clamped between said slotted walls, and means for holding said cap in position, said

means ensuring a substantially right angular disposition of the slots in one of said walls with respect to those in the other.

6. The combination with a strainer having a restricted outlet neck and a cap fitted thereover, of a bayonet joint for holding said cap in position on said neck, said joint comprising an angular groove formed in one of said members and a stud carried by the other and adapted to engage said groove, the latter being of gradually decreasing depth so as to bind against said stud to prevent accidental displacement.

7. A strainer comprising a bowl having a restricted neck at its lower end, a slotted wall extending across said neck, a cap fitted over said neck, the bottom of the cap being also slotted, and means to retain the cap in place upon the bowl with the slots of the bowl wall and the slots of the cap wall ar-

ranged transversely with respect to each other whereby to define a multiplicity of relatively small angular orifices.

8. The strainer described in claim 7 wherein a filter pad is interposed between the slotted walls of the bowl and cap.

9. A strainer comprising a plurality of plates each provided with a series of elongated slots and means to retain the plates in superposed relation with the slots of adjacent plates arranged transversely with respect to each other whereby to define a multiplicity of relatively small orifices.

10. The strainer defined in claim 9 wherein a filter pad is interposed between said plates.

In witness whereof, I hereto affix my signature.

PHILIP KEMPTER.
